LAVATORY FAUCET FITTING

Walter Baker, Jr., Louisville, Ky., assignor to
American Radiator & Standard Sanitary Cor-
poration, Pittsburgh, Pa., a corporation of
Delaware

Application April 1, 1953, Serial No. 24,285

Term of patent 14 years

(CL. D91—3)

To all whom it may concern:

Be it known that I, Walter Baker, Jr., a citizen of the United States, residing at Louisville, State of Kentucky, have invented a new, original, and ornamental Design for a Lavatory Faucet Fitting, of which the following is a specification, reference being had to the accompanying drawing, forming a part hereof.

Figure 1 is a front perspective view of a lavatory faucet fitting embodying my new design;

Figure 2 is a top plan view thereof on a reduced scale; and

Figure 3 is a front elevation thereof on a reduced scale.

The dominant features of the design reside in the portions shown in full lines.

I claim:

The ornamental design for a lavatory faucet fitting, substantially as shown and described.

WALTER BAKER, JR.
